UNITED STATES PATENT OFFICE.

EDGAR A. CALLESON, OF OAKLAND, CALIFORNIA.

DESIGN FOR A HAND-PROPELLED TOY VEHICLE.

Application filed March 10, 1927. Serial No. 21,083. Term of patent 3½ years.

To all whom it may concern:

Be it known that I, EDGAR A. CALLESON, a citizen of the United States, residing at Oakland, in the county of Alameda and State of California, have invented a new, original, and ornamental Design for Hand-Propelled Toy Vehicle, of which the following is a specification, reference being had to the accompanying drawing, forming part thereof.

Figure 1 is a perspective view of a hand-propelled toy vehicle showing my new design; and

Figure 2 is a similar view of it but looking from the rear.

I claim:

The ornamental design for a hand-propelled toy vehicle, as shown.

EDGAR A. CALLESON.
